UNITED STATES PATENT OFFICE

WILLIAM M. KELLY, OF WESTFIELD, NEW JERSEY, ASSIGNOR TO AMERICAN TYPE FOUNDERS COMPANY, OF JERSEY CITY, NEW JERSEY, A CORPORATION OF NEW JERSEY

PRINTING PRESS

Application filed December 10, 1926. Serial No. 153,991.

The present invention relates to printing presses of the bed and cylinder type and more particularly to devices for equalizing the surface speed of the cylinder and bed when the impression is on.

5 Although not limited thereto, the invention is illustrated and described as embodied in a two-revolution press, that is, a press wherein the cylinder makes two revolutions for each complete reciprocation of the bed, the cylinder not reversing but continually rotating in one direction. When the cylinder is in contact with the form on the bed, that is, during impression, it is essential that the 10 peripheral or surface velocity of the cylinder be identical with the rectilinear velocity of the bed. During the remainder of the cycle of the cylinder its surface speed may be anything to complete the required two revolutions thereof while the bed is making a complete reciprocation. Where the velocity of the bed continually changes, as occurs when the bed is reciprocated by a crank mechanism, it is necessary to vary the speed of the cylinder to accord with the velocity of the bed during impression. Various cylinder 15 driving mechanisms have been employed for this purpose. In one type the cylinder is driven directly by the bed during impression and at other times is disconnected therefrom and connected to a gear rotating with a uniform angular velocity. In another type the cylinder is driven at all times from a uniformly rotating shaft, and the variations of surface speed are effected by eccentric or non-circular gears alone or in combination with a planetary gear. Both of these types of mechanisms have obvious mechanical and operating defects. The clutching of the 20 cylinder to a bed and then to a uniformly rotating gear at each cycle, places great strains on the mechanism, causing rapid wear and making it impractical to operate the press at a high speed. The use of eccentric gears to effect the required velocity changes is mechanically unsatisfactory, and furthermore, it is difficult, if not impossible by such means, to effect an absolutely accurate equalization of the surface velocity of the cylinder 25 and the velocity of the bed.

In another form of mechanism, the driving gear is loosely mounted on an eccentric bearing and is rotated with varying velocities by means of a crank the outer end of which has a roller disposed in a curved guide attached to the gear. This device has not met 55 with any practical success.

The principal aim of the present invention is to provide in combination with means for reciprocating, at a non-uniform velocity, the bed of a press, of a cylinder driving mechanism of maximum mechanical and operating efficiency which will effect an absolutely accurate registration of the sheet on the cylinder with the form on the bed and which will enable the press to be run at the highest possible speed smoothly and without undue strain.

To this end, the cylinder driving mechanism of the present invention comprises a 70 train of gearing connecting a uniformly rotating shaft and a cylinder gear wheel, all the gears of the train being circular, constantly in full mesh and producing a uniform rotation of the cylinder when the positions of the gears are unaffected. The pitch circles of all of the gears are circular and always in rolling contact. In order to effect the required changes of the surface speed of the cylinder to correspond with that of the bed during impression, compensating mechanism is provided which comprises a member of the gear train mounted for bodily or planetary movement while at all times maintaining full driving engagement (the pitch circles are 75 always in contact) with its circular co-acting driving and driven gears, the bodily movement of said gear producing an increase or reduction in the speed of the cylinder gear accordingly as said planet gear is moved in 80 one direction or the other. Preferably the bodily movement of the planet gear is controlled by a cam, whereby the required variations in velocity of the cylinder are effected with great accuracy and smoothness, so that 85 absolute equalization of the surface speed of the cylinder and of the bed is obtained, and the press can be run at a very high speed without undue strain or wear.

Other objects and features of novelty will 100

be apparent from the description taken in connection with the drawings, wherein:

Fig. 1 is a sectional elevation taken substantially on the line 1—1 of Fig. 2;

5 Fig. 2 is a transverse sectional elevation taken substantially on the line 2—2 of Fig. 1;

Fig. 3 is a sectional plan view taken substantially on the line 3—3 of Fig. 1;

10 Fig. 4 is a sectional elevation taken through the axis of the bed operating gear;

Fig. 5 is a sectional elevation through one end of the cylinder, illustrating the driving connection between the cylinder gear and its shaft;

15 Fig. 6 is a diagrammatic elevational view of a modified form of cylinder driving mechanism; and

Fig. 7 is a plan view of the construction shown in Fig. 6.

20 The invention is applicable to presses of varying constructions and with many different mechanisms for reciprocating the bed.

In the embodiment of the invention illustrated in the drawings, the numeral 10 indicates the main frame of the press. This

25 frame comprises a rectangular housing formed with suitable openings in its walls to decrease the weight thereof and to give access to parts within the frame. It also provides a

30 support for various bearings.

For strengthening the housing and providing suitable supports for the mechanism, there is provided a central transverse web 10^a

35 connected on one side to an end wall of the housing by a central longitudinal member 10^b and connected on the other side to the opposite end wall by a longitudinal web 10^c which is offset from the central vertical plane of the

housing (Fig. 3).

40 The impression cylinder A, the inking mechanism B, the delivery table C, and other parts of the press not shown, are supported on longitudinal housing members 11 bolted onto the top side flanges of housing 10. The bed

45 D is supported on rollers 12 which are reciprocable in H-shaped tracks 13 supported on the tops of the end walls of housing 10 and on seats 14 on the central transverse web 10^a.

Each of the two sets of rollers is mounted in a

50 cage comprising a pair of longitudinal bars 15.

The press is driven by a motor 16 (Fig. 1), supported inside the housing 10, which rotates a transverse shaft 17 by means of a belt

55 18 passing over a pulley 19 rigid with the motor armature and over a relatively large pulley 20 keyed on shaft 17. Shaft 17 is journaled at its ends in bushings 21 and 22 in the sides of the housing and in an intermediate

60 bearing 23 in the longitudinal web 10^c (Fig. 2). Secured on shaft 17 is a pinion 24 which drives a gear 25 on a shaft 26 journaled in a bearing in the side of the housing and in a bearing in web 10^c. Shaft 26 projects out-

65 side the housing and carries a hand wheel H

for manual operation of the press. The other end of shaft 26 projects between web member 10^c and the side of the housing, and carries on this end a pinion 27 (Fig. 1). Pinion 27 meshes with a gear 31 keyed on a shaft 32

70

which is journaled in web 10^c and in the side of the housing. Shaft 32 projects inwardly from web 10^c and carries a crank 33 connected by a link 34 to a traveling gear 35 (Fig. 3).

75

As shown more clearly in Figs. 3 and 4, gear 35 is mounted on a shaft 36 and the bifurcated end of link 34 embraces the hub of gear 35.

80

Also mounted on shaft 36 is a pair of flanged wheels 37, the outer sides of which are engaged by collars 38 pinned on the shaft, whereby the entire assembly is held from lateral movement. Gear 35 meshes at its upper

85

side with a rack 39 fixed centrally on the underside of the bed and at its lower side with a stationary rack 40 bolted on frame member 10^b.

90

Wheels 37 roll on tracks 41 supported at the sides of rack 40. An arm 42 is mounted on each end of shaft 36 and the ends of these two arms are bolted to the outer bars 15 of the roller cages.

95

The bed D is reciprocated by the above described mechanism with a resultant movement compounded of the translation velocity of gear 35 and the rotary movement of said gear due to its engagement with stationary

99

rack 40, the velocity of the bed therefore being exactly twice the translation velocity of the gear. The velocity of the bed of course will vary from a minimum when the crank is on dead center, at which instant the velocity

100

is zero, to a maximum when the crank is about 90° from dead center. Due to the connection of the roller cages with shaft 36 through arms 42, the rollers are translated with the shaft,

105

so that their peripheral surfaces move with exactly the same velocity as that of the bed, whereby friction is reduced to a minimum.

The cylinder A is rotated at all times during the operation of the press in one direction by mechanism which will now be described.

110

Mounted in a bearing 43 in the housing is a sleeve 44 and rotatable therein is a shaft 45 which projects at both ends from the sleeve. The inner end of shaft 45 is supported in a bracket 46 bolted to the roller track 13 (Fig. 2), and rotatable on the outer

115

end of said shaft is a gear wheel 47 in mesh with the cylinder gear wheel 48. Fixed on shaft 45 at the inner end of sleeve 44 is a pinion 49 in mesh with the gear 31, and fixed on shaft 45 at the outer end of the sleeve is a pinion 50 of the same size as pinion 49.

120

Integral with sleeve 44 is an arm 51, and journaled in a bearing in the end of said arm is a gear 52 which meshes with gear 50 and with the internal gear teeth 53 of wheel 47.

125

Fixed on the inner end of sleeve 44 is an arm 54 formed with a gear segment 55 which meshes with a gear segment 56 on the end of an arm 57 pivoted at 58 to the side of the hous-

130

ing. Arm 57 has a roller 59 engaging a cam groove 60 formed in the outer face of gear 31.

The driving connection between gear 48 and the cylinder A is illustrated in Fig. 5. The cylinder shaft 62 is rotatable at each end in an eccentric bushing 63, journaled in the longitudinal housing member 11, these bushings being operated periodically by mechanism not shown herein for throwing the impression on and off. Gear 48 is rotatable on a bearing 64 bolted to the outside of housing 11. The cylinder shaft 62 is formed with a reduced end 62' which projects through a bore in bearing 64 with sufficient clearance to permit operation of the cylinder to impression on and off positions. Pinned on the end of reduced portion 62' is a disk 65 formed with a radial slot 66 in which works a block 67 secured to a pin 68 carried by gear wheel 48. This connection between the cylinder shaft and gear 48 permits a fixed position of the axis of gear 48 and a varying position of the axis of the cylinder, while maintaining the driving connection between the gear and cylinder. Thus gear 48 is at all times in full mesh with gear 47.

The average peripheral velocity of the cylinder is considerably greater than the average velocity of the bed, the cylinder having to make two complete revolutions while the bed is making one complete reciprocation. It is essential that the peripheral velocity of the cylinder be exactly equal to the velocity of the bed while the impression is on, so that there may be no slippage of the sheet being printed with respect to the form. The mechanism above described functions to effect this result with absolute accuracy and with great smoothness.

The direction of rotation of the cylinder is clockwise, looking at Fig. 1. The crank 33 is at dead center and the bed D is on the point of beginning its movement towards the left. A sheet has been taken by the cylinder and is being carried around thereby towards the bed and the cylinder is being driven by the gear train 31, 49, 50, 52, 53, 47 and 48. When the bed has moved to the left a short distance from the position shown, the register teeth on the cylinder begin to enter the register rack on the bed, and the impression is thrown on. Just prior to this time the cam 60 begins to move the roller on arm 57 further from the axis of shaft 32, so that arm 57 moves in a counter-clockwise direction (Fig. 1), operating arms 54 and 51 in a clockwise direction. Gear 52 carried by arm 51 is moved bodily about the axis of gear 47 in a clockwise direction (Fig. 1), and due to its engagement with gear 50 and with the internal gear 53, it will turn the wheel 47 in a clockwise direction. The resultant angular velocity of wheel 47, therefore, will be compounded of that produced by the gear train above referred to and that produced by

the bodily movement of gear 52. As the latter is opposite in direction to that of the former, it follows that the angular velocity of gear 47 and of the impression cylinder will be reduced from the value it would have if this compensating mechanism were not provided. The cam is so shaped that this reduction is of such value as to exactly equalize the peripheral speed of the cylinder with the varying speed of the bed during the entire time the impression is on.

In the embodiment of the invention illustrated the impression is on during about a quarter of a revolution of the crank 33 and gear 31, that is to say, the impression is on from shortly after the bed begins to move toward the left, as viewed in Fig. 1, and until the bed has nearly reached its maximum velocity and begins to slow down for the latter portion of the reciprocation toward the left. After the impression has been thrown off, the rotation of the cylinder may be as desired, and so the cam 60 for this portion of the cycle is shaped with the object of giving the smoothest action. In the embodiment of the invention illustrated, if the cylinder gear train were unaffected or unmodified, the cylinder would have the same surface speed as the bed only during the middle part of the reciprocation of the bed.

So from the beginning of the impression up to the time when the bed reaches about the middle part of its reciprocation, the action of the gear train must be modified so as to reduce the speed of rotation that the gear train would normally give the cylinder. This is done by swinging the arm 57 counter-clockwise, as viewed in Fig. 1, to thereby move the planet gear 52 in the direction to reduce the angular velocity of the cylinder. When the roller 59 on arm 57 reaches the high point M of the cam, the impression is thrown off and the balance of the cam may be shaped as desired. Obviously the cam may be shaped to produce any desired extent of synchronism between the cylinder and bed; for instance, if it were desired to continue the impression for a longer portion of the reciprocation of the bed, then after the bed reaches its middle point, as its velocity is decreased it would be necessary also to decrease the velocity of the cylinder. In this case, therefore, the cam surface succeeding the high point M would be carried further in toward the axis of the cam than as shown in Fig. 1. Of course the balance of the cam would be shaped to give the desired smooth action.

The compensating mechanism in the gear train to the cylinder gear, for effecting the required velocity changes of the cylinder, may take various forms within the scope of the present invention. Figs. 6 and 7, for example, show a modification of this compensating mechanism, in which the cylinder gear is operated by a worm driven at uni-

form velocity and movable axially to effect the necessary variation of cylinder velocity. In this modification the gears 25, 27 and 31 are mounted and operated in the same manner as described above. Also the bed D is operated by the traveling gear 35 connected to crank 33 by the link 34; the arm 57 is operated by the cam 60, and the cylinder gear 48' is connected by the pin and slot connection 68', 66', all in the manner above described. In the present modification, the cylinder gear 48' is a helical gear and meshes with a helical gear or worm 70 splined on a shaft 71 supported in suitable bearings 72 and 73. A bevel gear 74 is secured to the end of shaft 71 and meshes with a gear 75 on a shaft 76 to which is fixed a gear 77' driven from gear 25 through an intermediate gear 77. Worm 70 has rigid therewith a grooved collar 78 engaged by the forked end of an arm 79. Arm 79 is suitably pivoted at 80 and is integral with an arm 54' having a gear segment 55' in mesh with the gear segments 56 of arm 57. It will be understood that the axial movement of worm 70, effected by the operation of cam 60 on arm 57, will decelerate or accelerate the velocity of the cylinder according as the worm is moved towards the right or towards the left, looking at Fig. 6.

Although two forms of the invention have been illustrated, it is to be understood that the invention is not limited to these embodiments, but includes all modifications and changes which come within the scope of the appended claims.

Having thus described the invention, what is claimed as new and desired to be secured by Letters Patent is:

40. 1. In a bed and cylinder press, means for reciprocating the bed in combination with means for rotating the cylinder in one direction, said cylinder rotating means comprising a train of circular gears including a driving gear operating at uniform angular velocity and a driven gear bodily movable and having its pitch circle circular and always in contact with the circular pitch circle of said driving gear, and means for effecting bodily movement of said driven gear to equalize the peripheral velocity of the cylinder with the velocity of the bed while the impression is on.

55. 2. In a bed and cylinder press, means for reciprocating the bed in combination with means for rotating the cylinder in one direction, said cylinder rotating means comprising a train of circular gears having circular pitch circles always in contact including a driving gear having a uniform angular velocity and compensating mechanism between the driving gear and the cylinder for equalizing the peripheral velocity of the cylinder with the velocity of the bed when the impression is on.

3. In a bed and cylinder press, means for reciprocating the bed in combination with means for rotating the cylinder in one direction, said cylinder rotating means comprising a train of circular gears including a driving gear having a uniform angular velocity and a driven gear bodily movable and having its pitch circle circular and always in contact with the circular pitch circle of said driving gear, and a cam governing the bodily movements of said driven gear so as to equalize the peripheral velocity of the cylinder with the velocity of the bed while the impression is on.

4. In a bed and cylinder press, means for reciprocating the bed in combination with means for continuously rotating the cylinder in one direction with varying velocities, said cylinder rotating means including a gear wheel having internal and external teeth, a driven gear meshing with said external teeth, a pinion coaxial with said gear wheel operating at uniform velocity and an intermediate gear meshing with said pinion and said internal teeth, said intermediate gear being mounted for bodily movement about the axis of said gear wheel and pinion, and means for effecting bodily movements of said intermediate gear to vary the velocity of the cylinder.

5. In a bed and cylinder press, means for reciprocating the bed in combination with means for continuously rotating the cylinder in one direction, said cylinder rotating means including a gear wheel having internal and external teeth, a driven gear meshing with said external teeth, a pinion coaxial with said gear wheel operating at uniform velocity, and an intermediate gear meshing with said pinion and with said internal teeth, the intermediate gear being mounted for bodily movement about the axis of said gear wheel and pinion, and a cam for effecting bodily movements of said intermediate gear to vary the velocity of the cylinder.

6. In a bed and cylinder press, means for reciprocating the bed in combination with means for continuously rotating the cylinder in one direction with varying velocities, said cylinder rotating means including planetary gearing driven from a shaft of the press operating at uniform velocity, all the gears being circular and having circular pitch circles always in contact, and means for actuating said planetary gearing to vary the velocity of the cylinder.

7. In a bed and cylinder press, means for reciprocating the bed in combination with means for rotating the cylinder continuously in one direction with varying velocities, said cylinder rotating means including a gear wheel mounted on a fixed bearing adjacent the end of the cylinder, a shaft operating at constant speed and gearing connecting said shaft and said gear wheel, said gearing including compensating mechanism for varying

the velocity of the cylinder as required, and a cam controlling said compensating mechanism, all the gears being circular and having circular pitch circles in contact.

5 8. In a bed and cylinder press, means for reciprocating the bed in combination with means for rotating the cylinder continuously in one direction with varying velocities, said cylinder rotating means including a gear 10 wheel mounted on a fixed bearing adjacent one end of the cylinder, a shaft operating at constant speed and a gear train between said shaft and said gear wheel including a planetary gear, and a cam for effecting bodily movements of said planetary gear to vary the velocity of the cylinder as required, all the gears being circular and having circular pitch circles in contact.

15 9. In a bed and cylinder press, means for reciprocating the bed in combination with means for continuously rotating the cylinder in one direction with varying velocities, said cylinder rotating means comprising a planetary gear and a pair of circular gears meshing therewith, said gears having circular pitch circles always in contact, and means for effecting bodily movements of said planetary gear to vary the velocity of the cylinder as required.

20 10. In a bed and cylinder press, means for reciprocating the bed in combination with means for continuously rotating the cylinder in one direction at varying velocities, said cylinder rotating means comprising an epicyclic train of circular gears driven from a shaft 25 of the press operating at uniform velocity, and a cam for actuating the bodily movable member of said train to vary the velocity of the cylinder as required, all of the gears in 30 the train having circular pitch circles and being in contact.

35 11. In a bed and cylinder press, a bed, sliders supporting said bed for reciprocation, means to reciprocate said bed comprising a 40 rack on the underside of the bed, a parallel fixed rack, a gear meshing with said racks, a shaft on which said gear is rotatably mounted, means to reciprocate said shaft, and means to reciprocate said sliders with said shaft comprising a rigid member in which said sliders and shaft are journaled, whereby the spaced 45 relation of the axes of the sliders and shaft is maintained constant throughout the cycle of movement.

50 12. In a bed and cylinder press, a shaft, and means for reciprocating the bed and rotating the cylinder from said shaft, said means including an intermediate shaft, a train of gears for said shafts and the impression cylinder, 55 a planetary pinion moveable about the axis of said intermediate shaft, and means for giving planetary movement to said planetary pinion.

60 13. In a bed and cylinder printing press, 65 in combination, an impression cylinder hav-

ing a gear associated therewith, a reciprocating bed, means to reciprocate the bed and drive said gear comprising gearing including a shaft with a gear thereon, a pinion between the shaft gear and the cylinder gear, 70 a lever pivoted on said shaft and carrying said pinion, and means to oscillate said lever once for each cycle of the press.

14. The combination recited in claim 13 wherein the lever oscillating means comprises 75 a segment on the lever, a second segment meshing therewith, and a cam for actuating said second segment.

15. In a bed and cylinder printing press, in combination, a reciprocating bed, a cylinder, 80 means to reciprocate the bed, means to rotate the cylinder in one direction including a driving gear operating at a uniform angular velocity, a train of gears connecting said driving gear and cylinder, one of said train of gears 85 having internal teeth and another being bodily movable and meshing therewith, and means to oscillate said bodily movable gear to equalize the peripheral velocity of the cylinder and the velocity of the bed while the impression is on. 90

In testimony whereof I hereunto affix my signature.

WILLIAM M. KELLY.
